JACK

Robert K. Jeffrey, Bexley, Ohio, assignor to The Jeffrey Manufacturing Company, a corporation of Ohio

Application March 3, 1933, Serial No. 659,515

27 Claims. (Cl. 254—95)

In mining operations, it is customary to employ for drilling purposes a drill construction wherein the drill itself is mounted on a drill post supported between the ceiling and floor where the drilling operations are taking place, so that the drill may operate satisfactorily to prepare the deposit being mined for the usual blasting charge. Because of varying heights between the ceiling and the floor, the effective length of the drill post must be rendered adjustable in order to make it generally utilizable for any given location. In view of the restricted spaces in which the drilling operations frequently are necessarily carried out, it is essential that the required manipulations of the drilling equipment be rendered as accessible as possible to the operator, and it is therefore highly desirable that the equipment be simplified, both as to construction and operation, to the maximum possible extent.

In keeping with such efforts at simplification, the present invention provides novel improvements in adjusting mechanisms for varying the height of the drill post employed for carrying the usual drills employed in mining operations, the invention providing adjusting mechanisms which will be conveniently accessible to, and easily operable by, a single operator working in the very limited spaces frequently encountered in mine drilling operations.

The construction of the present invention generally includes a drill post for carrying a drill or similar tool, which is formed of a pair of sections, one slidable relative to the other, for effecting the required adjustment. The movable element is adjusted by novel mechanism forming the principal subject matter of the present invention, the mechanism being mounted as a unit on a sleeve or bushing secured to the stationary section, and co-acting with complementary actuating devices on the movable section for enabling the required adjustments to be made conveniently. Means are also provided for releasing the adjustment to enable ready removal of the tool from the drilling location when the drilling operations have been completed.

The details of the invention will be more readily understood by reference to the accompanying drawing, in which:

Fig. 1 is a fragmentary elevation of a drill post embracing the novel constructional features of the present invention;

Fig. 2 is a view similar to Fig. 1, but looking in a direction opposite to that of Fig. 1, and illus-

trating, in section, certain structural details of the movable section;

Fig. 3 is a detail view of a form of adjusting lever usable in the present construction;

Fig. 4 is an end view of the lever of Fig. 3, looking interiorly of the lever, and showing the internal construction thereof;

Fig. 5 is an elevation showing the improved jack post assembly of the present construction;

Fig. 6 is a view showing the post with drill mounted thereon as employed in service;

Fig. 7 is a sectional view taken on the line 7—7 of Fig. 5, looking in the direction of the arrows.

Referring more particularly to the drawing, it will be noted that the drill post construction comprises an outer, or stationary, section A, a relatively movable section B telescoping within section A, and a sleeve unit C embracing certain of the novel adjusting instrumentalities of the present invention.

The section A of the drill post is illustrated as being of a square configuration, and is provided with a series of notches adapted to have the drill D secured thereto in a known manner. The drill is provided with the usual boring auger E.

Interiorly, the section A is accurately bored to receive the telescoping tubular section B, aforesaid, this section being provided with a rack 1, which rack constitutes an adjusting means complementary to certain actuating devices which will be described in detail hereinafter.

These actuating devices are carried by the casting C, which is fitted over one end of the section to form a sleeve, and is clamped thereto in a suitable manner. The casting C is bored internally to enable the section B to operate therein, the parts being assembled so that the teeth of the rack 1 engage a pinion 2 mounted on shaft 3 extending transversely through the casting C.

Actuation of the shaft 3 and pinion 2 is accomplished by a lever 4 having a bifurcated fulcrum end 5 provided with an elongated slot 6 on each side, through which slot the shaft 3 passes. The lever 4 is secured in position on the shaft by means of a washer 7 and cotter-pin 8.

The lever 4 is of special construction, designed to operate a ratchet wheel 9 also mounted on the shaft 3 and suitably secured thereto in any desirable manner. Adapted to engage with this ratchet and to interlock therewith, is the pawl 10, turnably mounted with the shaft 11 being secured thereto by a pin 10a and normally held in

interlocking position with the teeth of the ratchet 9 by the tension of the spring 12.

It has been mentioned above that the lever 4 is of special construction to operate the ratchet

5 9. Accordingly, the lever is internally recessed, so that the ratchet 9 extends interiorly of this lever, which is provided with teeth 13 for engaging the teeth of the ratchet. The teeth 13 are disposed interiorly of the lever.

10 On the opposite ends of the drill post, and clamped to the sections A and B respectively, are off-set brackets 14 and 15 in which are mounted the points 16 and 16a. As will be seen from the drawing, the point 16 is yieldably mounted relative to the bracket 14, being maintained in extended position by a spring 17 bearing, respectively, against a collar 18 on the point 16 and the end of the bracket 14. This spring 17 is of considerable degree of stiffness, and serves as a buffer 15 for the post during manipulation of the adjusting mechanism, and enables a somewhat further movement of the sections A and B to take place in safety during adjustment of the post, even after the points 16 and 16a have been driven to 20 their limits into the ceiling and floor, respectively, of the drilling location by compression of said spring 17. Abutment or cotter-pin 18a retains the point 16 within the bracket 14.

25 It will be apparent that in order to hold the drill D and auger E in proper position, a considerable amount of pressure must be exerted on the adjusting mechanism, since the entire structure is maintained in position by the engagement of the points 16 and 16a with the ceiling and floor, or walls, of the location of the drilling operations. Therefore, a considerable load is imparted to the drill post, which must be relieved before the post can be removed after the drilling operation is completed.

30 40. In order to accomplish the removal of the post and drill, the adjusting mechanism, which it will be understood remains locked in adjusted position through engagement of the pawl 10 with the teeth of ratchet 9, must be released, which 35 is accomplished by first pressing on lever 4 sufficiently to lift the load of section A from the pawl 10 with accompanying disengagement of ratchet 9 from the pawl, when the pawl may be tripped. This tripping is done manually by the operator, 45 by pressing upon the lug 19, with sufficient force to turn the pawl against the action of the spring 12, which action, when carried sufficiently far, causes the spring to snap over dead center for maintaining the pawl in retracted position out of 50 engagement with the ratchet. Since, during the adjustment and operation of the drill and post, the points 16 and 16a have become embedded in the material at the boring operations, they must be forcibly released therefrom in order to enable 55 withdrawal of the post and drill, even after the pawl is released from its ratchet.

60 For this purpose, the sleeve C is provided with an abutment 20, engageable by the lever 4, whereby pressure exerted by the lever upon the abutment will loosen the points 16 and 16a from their 65 engagement and will enable the sections A and B to telescope together under the weight thereon, to effect release of the post and drill.

65 The section B is provided with an enlarged 70 head 21 for properly guiding the section B during its movements within the section A, and for holding the sections in proper alignment, by preventing turning therebetween owing to the polygonal configuration of the head 21 and the bore 75 within which it fits.

It is believed that the operation of this mechanism will be clear from the above description, and only a brief summary thereof need therefore be given.

75 From the above description, it will be apparent 5 that the lever 4 is not rigidly secured to the shaft 3, but because of the provision of the elongated slots 6 in the bifurcated fulcrum end 5 of the lever, sufficient play is allowed to enable the lever to be lifted sufficiently for the teeth 13 to disengage the ratchet 9, to enable the lever to be manipulated when desired, without affecting the ratchet. When it is desired to set up the drill, the sections A and B of the post are expanded as far as possible to effect a firm support for the drill. 10 This is accomplished by rotating the ratchet 9 by manipulation of the lever 4, so that the pinion 2 will successively engage the teeth of the rack 1. In this connection, it will be understood that the pawl 10 slides over the teeth of the ratchet 20 9 to enable the latter to be turned to effect expansion of the sections A and B, while interlocking with the ratchet to secure it against counter-rotation, the spring 12 holding the pawl in this position relative to the ratchet. For rotating the 25 ratchet, obviously the teeth 13 in the lever 4, are brought into progressive engagement with the teeth of the ratchet, and the lever 4 is swung to advance the rack 1. To effect the progressive 30 advancement of the rack, after each time the lever is operated to move the ratchet, it is lifted to disengage the teeth 13 from the ratchet as the lever is brought back for the next operation. These manipulations are repeated until the sections A and B are expanded and the points 16 35 and 16a are pressed as far as possible into supporting position. It will be apparent that at the end of this adjustment the spring 17 acts as a buffer between the post and points enabling a cushioning effect to be obtained between the 40 post and points. The apparatus is then ready for drilling operations.

45 When it is desired to release the jack the lever 4 is moved down sufficiently to relieve the pressure of the ratchet 9 on the pawl 10 so that the 50 pawl shifter 19 may easily be moved manually on the shaft 11 until the spring 12 passes over dead center where it will hold the pawl 10 out of engagement with the ratchet 9. That is to say, when sufficient downward pressure is exerted on 55 the lever 4 to free the pawl 10 from the ratchet 9, the pawl shifter 19 may be positively actuated manually to release the pawl 10 from the ratchet 9 and the spring 12 being on dead center will hold the pawl 10 in released position after the pawl 55 shifter 19 is released.

60 After the pawl 10 has been released from the ratchet 9 the pressures on the ends of the jack tend to keep the ratchet 9 in interlocking connection with the teeth 13 carried by the lever 4. 65 In the event that there should be a subsidence of the roof of the mine room or entry after the jack has been anchored, there will be a heavy pressure exerted on the sections A and B by virtue of the load thus transferred to the jack. Consequently, when the pawl 10 is released from the ratchet 9 in the manner stated the subsidence pressure may be so great as to tend to rotate the ratchet 9 while in interlocking connection with the teeth 13 and tend to take the lever out of the control of the operator. The abutment 20 rigidly connected to the section A in stationary position adjacent to the enlarged portion 4a acts as a safety device in preventing sudden movement of the 70 75 75

lever 4 when the pawl 10 is released from the ratchet 9.

It will thus be seen that even after the pawl 10 is released from the ratchet 9 and held by the spring 12 in released positions, the jack sections are still held in anchored positions by the ratchet 9 engaging the teeth 13 and the enlarged portion 4a engaging the stationary abutment 20. Now upon movement of the lever 4 in a clockwise direction as viewed in Fig. 1, the abutment 20 will act as a fulcrum for the lever 4 while the teeth 13 are released from the ratchet 9. During such release of the teeth 13 from the ratchet 9 the shaft 3 remains in stationary position in fixed relation to the jack sections but by reason of the loop 5 having an elongated slot 6 therein, the latter may slide on the shaft 3 during movement of the teeth 13 away from the ratchet 9. As soon as the teeth 13 are released from the ratchet 9 the jack sections collapse to effect release of the jack from its anchored position, without any sudden movement of the lever 4. In this manner, notwithstanding the heavy subsidence pressure which may be exerted upon the jack, after it has been set in anchored position, the jack may be readily and safely released for easy removal from its drill supporting position.

It may be mentioned that the drill D is mounted on the square section A of the post, which section is provided with the square notches 22. The drill D is mounted on a supporting member 23 suitably held in the notches 22, this support, in co-operation with the points 16 and 16a, being such as to provide a mounting of the drill on the post to enable operation of the drill in any desired direction in rectilinearly related axes. A clamp 24 is provided for securing the drill in the desired position, and because of the square configuration of the notches 22, it is immaterial whether the post be employed as shown, with the square section A as the upper section, or whether it is inverted, the square notches affording the same support for the member 23 in either position of the post, enabling the operator to drill nearer the roof or floor.

With reference to Fig. 7, it will be observed that the shoulder 25 provides a means for preventing accidental separation of the sections after the parts are assembled, this shoulder preventing a free or unobstructed passage of the head 21 from the bore of the section A. This shoulder 25 marks the boundary between the circular portion of the bore 26, and the non-circular portion 27.

It will also be noted that the parts of the device are clamped together by a clamp 28 integral with the sleeve C. This clamp, as will be seen from Fig. 7, comprises the parts 29 and 30, bolted together tightly by bolt 31, which is secured in position by a nut 32, thus holding the casting C securely in position on the section A.

It may be mentioned also that when the jack is put in position, the operator may hold it by pressing with his foot upon bracket 15 and then manually lifting section A as far as possible. Necessary final adjustment may then be accomplished by a relatively few manipulations of lever 4.

Obviously those skilled in the art may make various changes in the details and arrangement of parts without departing from the spirit and scope of the invention as defined by the claims hereto appended, and I wish therefore not to be restricted to the precise construction herein disclosed.

Having thus described and shown an embodiment of my invention, what I desire to secure by Letters Patent of the United States is:

1. A mine jack comprising a body formed of a pair of sections adjustable relative to each other, instrumentalities for spreading the sections, the instrumentalities tending to become interlocked under pressure of a load on the jack, and means for applying a counter-pressure to the said instrumentalities to break the interlock therebetween for freely releasing the sections after spreading thereof to enable the sections to freely collapse.

2. A jack comprising a body formed of a pair of sections adjustable relative to each other, and instrumentalities for spreading the sections comprising ratchet mechanism operatively connected with the sections, and a lever for operating the ratchet mechanism, the said lever being provided with a pawl for operating the ratchet mechanism, the pawl becoming interlocked with the ratchet mechanism under pressure of a load upon the jack, the lever and having means enabling the pawl to be released from the ratchet mechanism upon application of counter-pressure upon the lever and pawl to effect free release of the sections, and abutments on the lever and jack adapted to be brought into operative engagement by suitable manipulation of the lever for enabling a sufficient pressure to be applied therebetween for separating the said pawl and ratchet mechanism for operating the lever independently of the ratchet mechanism.

3. A jack comprising a body formed of a pair of sections, one section telescoping within the other, and instrumentalities for spreading the sections comprising ratchet mechanism operatively connected with the sections, and a lever for operating the ratchet mechanism, the said lever being provided with a pawl for operating the ratchet mechanism, and having means enabling the lever to be lifted for disengaging the pawl from the ratchet mechanism for operating the lever independently of the ratchet mechanism, and means on the outer section engageable by the lever for effecting separation of the pawl from the ratchet mechanism for releasing the sections after expansion thereof.

4. A mine jack comprising a body formed of a pair of sections adjustable relatively to each other, instrumentalities for spreading the sections and becoming in locked engagement under pressure of a load on the jack, and means on the jack engageable by certain of the said instrumentalities for releasing the sections for free collapse after the spreading thereof.

5. A mine jack comprising a body formed of a pair of sections adjustable relatively to each other, instrumentalities for spreading the sections and tending to become interlocked under pressure of a load on the jack, and an abutment member on the jack engageable by certain of the said instrumentalities for enabling the said interlocking pressure to be counteracted for releasing the sections for free collapse after the spreading thereof.

6. A mine jack comprising a pair of sections adjustable relatively to each other, adjusting mechanism for the sections, means for operating the sections, the adjusting mechanism and operating means tending to become interlocked under pressure of a load on the jack when the sections are fully extended, and means for exerting a counter-pressure on the operating means and adjusting mechanism for overcoming the inter-

locking pressure of the load for releasing the sections to enable the same to freely collapse.

7. A jack comprising a pair of sections adjustable relatively to each other, adjusting means for the sections carried by one of the sections, complementary adjusting means on the other section operatively interconnected with the aforesaid means, and operating means normally engaging the adjusting means to operate the same, and becoming interlocked therewith under pressure of a load on the jack, and means for counteracting the said pressure for effecting disengagement between the adjusting means and operating means to release the said sections to enable free collapse thereof.

8. A jack comprising a pair of sections telescopically adjustable relatively to each other, adjusting mechanism including a ratchet for effecting adjustment of the sections and a lever for operating the ratchet, the said lever being provided with teeth enclosed within the lever for operatively engaging the said ratchet, the teeth and ratchet tending to become interlocked under pressure exerted by a load on the jack, and means enabling a counter-pressure to be applied to the lever to separate the teeth thereof from the ratchet for releasing the sections to enable free collapse thereof.

9. A jack comprising a pair of sections adjustable relatively to each other, and mechanism for spreading the sections, the mechanism including a ratchet and a lever fulcrumed at one end to one of the sections and provided with a pawl for engaging the ratchet for operation thereof, the pawl and ratchet tending to become interlocked under pressure exerted by a load on the jack, the fulcrumed end of the lever being provided with a loop upon which the lever is adapted to be manipulated, and means enabling a counter-pressure to be applied to the lever to enable the lever to slip on the loop to disengage the pawl from the ratchet for releasing the said sections to enable free collapse thereof.

10. A jack comprising a pair of sections, one section telescoping within the other, mechanism for extending the sections relatively to each other, the said mechanism including a shaft, a pawl and ratchet mechanism on the shaft and a lever for operating the mechanism, the said pawl being a part of the lever, the said lever being fulcrumed on the shaft and being provided with a loop through which the shaft extends, the pawl and ratchet mechanism becoming interlocked under pressure of a load upon the jack, and means enabling a counter-pressure to be exerted on the lever for lifting the lever along the said loop to disengage the said pawl and ratchet mechanism for freely releasing the sections.

11. A mine jack comprising an outer section and an inner section, a sleeve unit mounted on the outer section, a rack on the inner section, and adjusting mechanism mounted on the sleeve unit and adapted to engage the said rack for effecting a relative spreading of the sections, the said adjusting mechanism comprising a lever provided with a pawl, and a ratchet engageable by the said pawl, the pawl and ratchet tending to become interlocked under pressure exerted by a load on the jack, and cooperating means on the lever and sleeve for counteracting the said pressure to effect a separation of the pawl and ratchet to enable the sections to freely collapse.

12. A jack comprising an outer section and an inner section, a sleeve unit mounted on the outer section, a rack on the inner section, and adjust-

ing mechanism mounted on the sleeve unit and adapted to engage the said rack for effecting a relative spreading of the sections, the said adjusting mechanism comprising a lever provided with a pawl, and a ratchet engageable by the said pawl, the pawl and ratchet tending to become interlocked under pressure exerted by a load on the jack, and cooperating abutments on the lever and sleeve for enabling a purchase to be effected upon the lever to separate the pawl from the ratchet when the lever is operated counter to the operation thereof which produces said spreading for releasing the sections to enable them to freely collapse.

13. A jack comprising a body formed of a pair of sections adjustable relatively to each other, adjusting instrumentalities for adjustment of the sections and including a ratchet, a lever provided with teeth adapted to engage the ratchet for operation thereof, a pawl releasably engaging the ratchet, means enabling the lever to be moved to effect disengagement of the teeth thereof from the ratchet, and cooperating abutment members on the jack and lever to enable the lever to obtain a purchase on the jack to release the sections for free collapse thereof.

14. A jack comprising a body formed of a pair of sections adjustable relatively to each other, means for extending the sections, the said means including cooperating pawl and ratchet mechanism, and a lever for operating the ratchet mechanism, the said lever being disengageable from the ratchet mechanism for collapsing the sections, an abutment member on the jack adapted to be engaged by the lever upon suitable manipulation of the lever to enable pressure to be applied between the lever and ratchet mechanism to effect disengagement therebetween for releasing the sections to enable the sections to freely collapse, and means for holding the pawl out of engagement with the ratchet for maintaining the ratchet released when the pawl is moved past dead center position in a direction away from the ratchet.

15. A jack adapted to be subjected to the pressure of a heavy load, comprising a pair of sections adjustable relatively to each other, mechanism for spreading the sections including an operating lever normally in operative engagement with the remaining mechanism for extending the sections and becoming locked with the said mechanism under action of the pressure of the load upon the jack, means enabling free manipulation of the lever about the locked engagement, and means engageable by the lever for enabling pressure exerted upon the lever to break the said locked engagement for releasing the sections to enable the sections to freely collapse.

16. A jack adapted to be subjected to the pressure of a heavy load, comprising a pair of sections adjustable relatively to each other, mechanism for spreading the sections including an operative lever and a ratchet, the said lever being provided with teeth engageable with the said ratchet for operating the ratchet to extend the sections, the teeth of the lever coming into locked engagement with the ratchet under the pressure of the load on the jack while, however, allowing the lever to be manipulated around the ratchet, and an abutment on the jack engageable by the lever upon suitable manipulation thereof, whereby a purchase may be obtained upon the lever to break the engagement between the ratchet

and teeth of the lever for releasing the sections to enable the sections to freely collapse.

17. A mine jack comprising relatively adjustable sections, operating mechanism for the sections for effecting adjustment thereof, the mechanism becoming self-locking under influence of pressure applied to the ends of the jack, and means enabling a counter-pressure to be exerted on the mechanism sufficient to overcome the aforesaid pressure to release the said mechanism for enabling the sections to freely collapse.

18. A jack comprising a pair of relatively adjustable sections, pawl and ratchet mechanism between said sections for anchoring the jack, a shoe yieldingly connected to one end of one of said sections, and means for operating the ratchet to exert additional pressure on said yieldingly connected shoe to permit release of the pawl when said jack is to be released from its anchored position.

19. A jack comprising a pair of telescoping sections each non-circular in cross-section to prevent relative rotation, laterally extending brackets at the remote ends of said sections, spaced-apart anchoring points mounted in alignment with each other on said brackets, a yielding connection between one of said points and its bracket, and pawl and ratchet means for moving said telescoping sections relatively to each other to effect the application or release of said anchoring points.

20. A jack comprising relatively adjustable sections, mechanism comprising a pawl and a ratchet for spreading said sections, a retaining pawl for said ratchet, a lever for actuating said first-named pawl to rotate said ratchet, mechanism affording spaced fulcrums for said lever, and means for supporting said lever for engagement with one of said fulcrums when the first-named pawl rotates said ratchet and for engagement with the other fulcrum when the jack is to be released.

21. A jack comprising two sections relatively adjustable, means comprising pawl and ratchet mechanism including a lever for moving said sections to anchor the jack, a releasable retaining pawl for the ratchet, abutment mechanism cooperating with said lever for locking said sections in anchored positions when said retaining pawl is released, said lever including means cooperating with said abutment mechanism to release said pawl from its ratchet while said retaining pawl is released, to effect release of the jack from its anchored position.

22. A jack comprising relatively adjustable sections, means for moving said sections relatively to each other to anchor the jack and hold the same anchored, an operating lever having a slot in the fulcrum end thereof, and abutment mechanism coacting with said slot to release said moving means to enable said jack to be released.

23. As an article of manufacture, an operating lever for a jack, comprising a fulcrum slot, a pawl, and an extension adapted to engage an abutment on the jack to release the pawl as permitted by said slot.

24. A jack comprising two sections, a pinion on one section, a rack on the other section, a ratchet,

a shaft secured to said pinion and to said ratchet, an operating lever having a slot through which said shaft extends, a fixed abutment on the section carrying the pinion and the ratchet, a pawl on said lever releasably engaging said ratchet, a releasable retaining pawl for said ratchet operable independently of the pawl on said lever, and an extension on said lever in position to engage said abutment to act as a fulcrum to release said first-named pawl from said ratchet as permitted by said slot.

25. A mine jack comprising a pair of telescoping sections each provided with means to prevent relative rotation therebetween, laterally extending brackets at the remote ends of said sections, spaced-apart anchoring means mounted in alignment with each other on said brackets, and pawl and ratchet means for expanding said sections and for releasing said sections for free collapse.

26. A mine jack comprising a pair of telescoping sections, a rack carried by one of said sections, means connected between one section and the rack on the other section for expanding said sections and maintaining them in expanded condition, said means comprising an actuating pawl and a releasable retaining device, a handle connected to said actuating pawl for operating the expanding means when the handle is moved in one direction, said sections being maintained in expanded condition by said retaining device, an abutment on one section in position to serve as a fulcrum for said handle when the latter is moved in a direction opposite to that required to effect expansion of said sections, and means actuated by said handle when said abutment becomes effective as a fulcrum to release the actuating pawl after the retaining device has been released and thereby effect release of the mine jack from its anchoring position.

27. A mine jack comprising a pair of telescoping sections, a rack carried by one section, means connected between one section and the rack on the other section for expanding said sections and maintaining them in expanded condition, said means comprising an actuating pawl and a releasable retaining pawl, an actuating handle connected to the actuating pawl for expanding said sections when the handle is moved in one direction, said sections being maintained in said expanded condition by said releasable retaining pawl, an abutment on one of said sections in position to be engaged by said handle when the latter is moved in a direction opposite to that required to secure expansion of said sections, and mechanism actuated by said handle when engaging said abutment to effect such movement of said actuating pawl as to release the same, the construction and arrangement being such that when a load is on the jack the said lever may be actuated to expand the said sections sufficiently to permit manual release of the retaining pawl whereupon the lever may be released to effect transfer of the load on the jack to said actuating pawl and by reverse movement of the lever the abutment may be engaged as aforesaid to secure release of the actuating pawl and the collapse of said sections.

ROBERT K. JEFFREY.
